UNITED STATES PATENT OFFICE

GROSVENOR N. ALLEN AND ELMER H. KREPS, OF ONEIDA, NEW YORK, ASSIGNEES TO
ONEIDA COMMUNITY, LIMITED, OF ONEIDA, NEW YORK, A CORPORATION OF NEW
YORK

DESIGN FOR A DISH OR SIMILAR ARTICLE

Application filed October 6, 1932. Serial No. 45,250. Term of patent 14 years.

To all whom it may concern:

Be it known that we, GROSVENOR N. ALLEN and ELMER H. KREPS, citizens of the United States, residing at Oneida, county of Madison, State of New York, have invented a new, original, and ornamental Design for a Dish or Similar Article, fully described and represented in the following specification and the accompanying drawing, forming a part of the same, in which,—

Figure 1 is a plan view of a dish showing our new design,

Figure 2 is a cross-section on the line 2—2 of Figure 1, and

Figure 3 is a cross-section on the line 3—3 of Figure 1.

The essential feature of our design is the ornamentation on the dish or similar article.

We claim:

The ornamental design for a dish or similar article as shown and described.

In testimony whereof we have hereunto set our hands.

GROSVENOR N. ALLEN.
ELMER H. KREPS.
